DENTAL TOOL

Joseph B. Hersh, Flushing, N. Y.

Application June 21, 1947, Serial No. 756,145

5 Claims. (Cl. 32—40)

1

This invention relates to method and apparatus for removing dental impression bands.

An impression band is a tubular band, usually of copper, used in present dental practice to obtain an impression of a tooth as for example for the purpose of making a cap or crown. According to present dental practice the tubular band is filled or partly filled with melted wax and the band is then inserted over the tooth of which an impression is desired and wax is thus brought into contact with the surface of the tooth and as it hardens it takes the form of the tooth. The hardened wax adheres to the tooth so that it is difficult to remove the band and considerable force is required to do so, especially since the band must be removed without sidewise movement which would impair the impression.

It is an object of this invention to provide an improved method and apparatus for removing dental impression bands.

Another object of the invention is to provide simple, practical and efficient apparatus for removing dental impression bands.

Another object of the invention is to provide apparatus for removing impression bands whereby the band is aligned along a path the center line of which is parallel to the axis of the tooth.

Another object of the invention is to provide means of the above described kind whereby the dentist is assured of obtaining a firm grip on an impression band and of lifting the band from the tooth without sidewise movement.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which,

Figure 1 is a front elevational view partly in section of apparatus embodying the invention, in operative position;

Figure 2 is a top plan view of the device shown in Figure 1; and

Figure 3 is a perspective view with some parts in exploded relation.

In the practice of my invention a dental band 10 is employed which may be annular in shape and which at its top is provided with a lateral

2

flange 12 adapted to give purchase to means for removing the band from a tooth. In the embodiment of the invention illustrated herein this means comprises a fork-like member 14 the bifurcated ends of which are spaced apart sufficiently to embrace the body of the band 10 and to engage under the lateral flange 12, and means for supporting and moving the member 14 in a straight line. This means comprises the jaws 16 and 18. Jaw 16 intermediate its ends is pivotally attached by pivot 20 to the forward end of the S-shaped member 22. Similarly the jaw 18, intermediate its ends is pivotally attached by pivot 24 to the S-shaped member 26. The members 22 and 26 are crossed and pivotally interengaged by pivot 28. Each of the members 22 and 26 is shaped so that it is substantially U-shaped in cross section and the forward portion of each is stamped out along its median longitudinal line. Thus the forward end of member 22 comprises the spaced arms 22^a and 22^b pivotally connected by pivot 20 on opposite sides of jaw 16, and similarly member 26 comprises spaced arms 26^a and 26^b pivotally connected by pivot 24 on the opposite sides of jaw 18. Pivot 28 may extend through the superimposed arms 22^a and 26^a and the superimposed arms 22^b and 26^b or it may consist of a plurality of aligned pivots joining arms 22^a and 26^a and 22^b and 26^b respectively.

On the inner surface of member 22 a pin or lug 30 is provided and on the inner surface of member 26 a similar pin or lug 32 is provided. The rear end of jaw member 16 extends between the parallel arms 26^a and 26^b of member 26 and its rear end is bifurcated providing a bearing surface 34 which is adapted to engage and abut against the stop or pin 32. And similarly the rear end of jaw member 18 projects between the arms 26^a and 26^b of member 26 and its inner end is bifurcated providing a bearing surface 36 which is adapted to engage and abut against the stop or pin 30. Within the trough of the U-shaped member 22 behind pivot 28 a coil spring 38 is provided, one end of which is secured at 40 to one of said bifurcated arms of jaw member 18 and the other end of which is secured to an ear 42 which may be stamped out of said member 22 and bent inwardly. Similarly in the trough of the U-shaped portion of the handle member 26 a spring 44 is provided the front end of which is attached at 46 to one of the bifurcated arms of jaw member 16 and which at its other end may be secured to the lug 48 which may be stamped out of the member 26 and bent inwardly.

Projecting upwardly from jaw 18 is a pin 50 and

jaw 16 is provided with a bore 52 aligned with pin 50. The forward end of pin 50 projects into the bore 52 and travels therein as the members 22 and 26 are moved toward one another.

The jaw 16 is provided at its front end with a bracket 54, which as illustrated herein is U-shaped and extends around the jaw 18 with its ends secured to the respective sides of jaw 16 as by screws s. The forward end of jaw 18 is provided with a concavity or seat 56 adapted to receive the stem 15 of fork-like member 14 which may be readily inserted in or removed therefrom.

No claim is made herein to the pincer-like structure described above apart from the bracket-like structure 54 and the fork-like member 14 and the means for seating member 14 for movement with jaw 18. It will be understood that when the portions of members 22 and 26 behind the pivot 28, which constitutes the handles of the pincer-like device, are moved together the jaws 16 and 18 will be moved relatively and such movement will be a straight line rather than an angular movement due to the pivotal engagement between members 22 and 26 and jaws 16 and 18 respectively, and the pivotal interengagement of members 22 and 26, and the guide effect obtained by the travel of pin 50, on jaw 18, in the bore 52 in jaw 16.

In using the device described herein in accordance with my invention the fork-like member 14 of a size adapted for the diameter of the dental impression band 10 employed is inserted in the cavity or seat 56 therefor. And after the forked end of member 14 has been inserted around the dental band 10 which it is desired to remove from a tooth the impression of which has been taken, and is firmly engaged under lateral flange 12 of the band, the bracket 54 is rested on and adjacent tooth (or on a bridging member placed across other teeth in the event there is no adjacent tooth), and the rear ends of members 22 and 26 are moved together. Because jaw 16 is secured to bracket 54 it remains stationary and jaw 18 moves toward it without angular or lateral motion thus similarly moving member 14 and the dental band 10 engaged by it. The extent of straight line movement thus imparted to the dental band 10 is sufficient to lift it entirely off the tooth of which the impression is desired, and thus a perfect impression may be obtained without the inaccuracy often resulting when the band is wiggled from side to side in attempting to break the adhesion between the wax and the tooth in pulling the band from the tooth manually.

Dental impression bands may be made in a number of different sizes and as many different sized fork-like members 14 are provided as are required for engaging the various sizes of bands. As has been explained one member 14 may be readily substituted for another of a different size corresponding to the size of impression band to be removed.

It will thus be seen that there has been provided by this invention a method and apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accom-

panying drawing is to be interpreted as illustrative and not in a limiting sense.

What I claim is:

1. A dental tool for use in conjunction with an impression band comprising upper and lower jaws, handles for each, the handles being pivoted together and the upper handle being pivoted to the lower jaw ahead of said pivot, and the lower handle being pivoted to the upper jaw ahead of said pivot, the upper jaw having a vertical bore or aperture adapted to receive a stud extending vertically up from the lower jaw thus preventing relative movement between the upper and lower jaws except toward and away from one another in a vertical plane, a U-shaped band extending around the lower jaw and secured by its ends to the opposite sides of the upper jaw, said band providing a base adapted to rest on a fixed surface so that when the handles are pressed together the position of the upper jaw is fixed and the lower jaw rises thus lifting the band.

2. A dental tool for use in cooperation with a dental band having engagement means thereon to provide a purchase for the tool comprising, upper and lower jaw members, a pair of crossed handles pivotally joined together intermediate their ends, the forward end of the lower handle being pivotally joined to the upper of said jaws and the forward end of the upper handle being pivotally joined to the lower of said jaws, pin and slot means interconnecting the rear end of said upper jaw to the said upper handle behind the pivotal connection between the handles, pin and slot means interconnecting the rear end of the said lower jaw to said lower handle behind said pivotal connection between said handles, a spring member interconnected between the rear end of said upper jaw and said upper handle adjacent its rear end, a spring member interconnected between the rear end of said lower jaw and said lower handle adjacent its rear end, and a standard adapted to be rested on a fixed surface and connected to one of said jaws whereby when said handles are compressed the other of said jaws will be caused to move in a straight path toward the jaw to which said standard is connected, and means supported on said movable jaw adapted to engage with said engagement means on said dental band.

3. A dental tool for use in cooperation with a dental band having engagement means thereon to provide a purchase for the tool comprising, upper and lower jaw members, a pair of crossed handles pivotally joined together intermediate their ends, the forward end of the lower handle being pivotally joined to the upper of said jaws and the forward end of the upper handle being pivotally joined to the lower of said jaws, each of said upper and lower jaws being bifurcated at the rear end, each of said handles having a pin projecting inwardly to the rear of the said pivotal connection between the handles, said pins being adapted to seat between the bifurcations at the rear ends of said jaws respectively, a spring interconnecting the rear of the upper jaw to the upper handle adjacent its rear end, a spring interconnecting the rear of the lower jaw to the lower handle adjacent its rear end, a standard attached to one of said jaws and extending beyond the other of said jaws without interfering with the movement of the other of said jaws, and means attached to the other of said jaws adapted to extend around said dental band under its said engagement means and to engage under said engagement means and

move the band in a straight line substantially parallel to the axis of the band when the device is rested on said standard and the said handles of the device are moved together.

4. A device as claimed in claim 2 in which one of said jaws has a stud thereon projecting toward the other of said jaws, and the other of said jaws is bored providing a guideway adapted to receive the free end of said stud therein as the jaws are moved together, said stud and bore cooperating with the pin and slot connections between the rear ends of said jaws and said handles respectively to prevent angular movement of the jaws as they are moved together when the said handles are compressed together.

5. A device as claimed in claim 2 in which one of said jaws has a stud thereon projecting toward the other of said jaws, and the other of said jaws is bored providing a guideway adapted to receive the free end of said stud therein as the jaws are moved together, said stud and bore cooperating with the pin and slot connections between the rear ends of said jaws and said handles respectively to prevent angular movement of the jaws as they are moved together when the said handles are compressed

together, and means attached to the other of said jaws adapted to extend around said dental band under its said engagement means and to engage under said engagement means and move the band in a straight line substantially parallel to the axis of the band when the device is rested on said standard and the said handles of the device are moved together.
